UNITED STATES PATENT OFFICE.

NORMAN C. HUCKESTEIN, OF PITTSBURGH, PENNSYLVANIA.

RADIATOR GUARD.

Application filed September 23, 1920. Serial No. 412,171.

To all whom it may concern:

Be it known that I, NORMAN C. HUCKESTEIN, citizen of the United States, residing at Pittsburgh, in the county of Allegheny and State of Pennsylvania, have invented certain new and useful Improvements in Radiator Guards, of which the following is a specification.

My invention consists of an improvement 10 in radiator guards for automobile trucks and the like. It has for its object to provide a guard which will protect the radiator from injury by means of a series of vertically arranged spring-controlled pivoted 15 blades or wings adapted to be depressed or closed upon being struck by any object, and to re-act upon release of pressure. The wings are also capable of being partly or wholly closed for regulation of the air supply, and the device is constructed and adapted 20 to operate in the manner more fully hereinafter described.

In the drawings which show one preferred embodiment of the invention—

25 Fig. 1 is a view of the device in front elevation, with the wings in normal extended position.

Fig. 2 is a transverse section on the line II, II of Fig. 1.

30 Fig. 3 is a view of the device in side elevation as mounted on the truck frame.

Fig. 4 is a detail view showing the manner of retaining the wings partly closed.

Fig. 5 is a cross section on the line V, V 35 of Fig. 4.

Fig. 6 is a view like Fig. 4 but showing the wings entirely closed.

Fig. 7 is a cross section on the line VII, VII of Fig. 6.

40 Fig. 8 is a detail view showing the manner of pivotally mounting the wings.

In the drawings 2 is the chassis frame of a truck of ordinary construction provided with the usual radiator 3 mounted thereon.

45 The radiator guard is composed of a hollow rectangular metal frame having a base 4 and top 5 and side bar members 6, 6. The base 4 of such frame is mounted upon a plate 7 and an angle bar 8 and suitably bolted together for rigid construction, the angle member being also bolted to the front 50 of the frame 2, in the manner shown.

55 Side braces 9 are bolted to the top of the rectangular frame at each side, as at 10, and extend backwardly and are similarly bolted to the sides of the chassis frame, as

at 11, for securely maintaining the frame in position.

The top and bottom of the main rectangular frame is provided with inwardly extending sills 12 and 13 respectively, and between the top and bottom members are the series of vanes or wings 14 each having a pivotal terminal 15 at each end. These terminals are seated in suitable receiving 60 sockets or bearings in the bottom and top sills 12 and 13 respectively, with an intervening washer 16 so as to ensure free swinging action of the several vanes, back against limiting flanges 12^a and 13^a.

65 Each vane is maintained in its opened position by means of a strong spiral spring 17 secured by one end to a rearwardly extending arm 18 of the vane, and by the other end to the upwardly extending flange 19 of the 70 plate 7. Arms 18 are so arranged with relation to the vanes, that they will be maintained by the pull of the spring at an outwardly disposed angle at each side of the vertical central portion of the guard, as 75 shown, i. e., divergently towards the right and left.

80 The advantage of this arrangement is that the vanes at one side or the other are in a position to be easily deflected by a glancing blow, or a head-on contact, and will fold inwardly and close the opening to the radiator, so as to more completely cover and protect it. Upon release of pressure the vane or 85 vanes will re-act by spring tension to their 90 normal position, as in Figs. 1 and 2.

95 For the purpose of positively holding the vanes either partly or entirely closed, I provide a cross rod or bar 20 which may be thrust through holes 21 or 22 in the side bar members 6 of the main frame across the front portions of the vanes, and retained by terminal nuts as shown in Figs. 4—5 and 6—7. By this means the vanes may be utilized to control the circulation of air between the vanes to the radiator, while also protecting it from impact or injury arising from collision.

100 As shown the vanes are arranged in two equal series at each side of the middle of the frame, and a central upright brace or bar 23 may be inserted to strengthen the frame and also close the middle space, as 105 shown in Figs. 1 and 2. The frame itself may be of any suitable construction, as 110 structural steel framed together at the corners, or it may be of a simple steel casting

with one of the steel members 12 or 13 made separable to facilitate insertion or removal of the several vanes.

The device as a whole is very strong and 5 serviceable, simple in construction and not liable to get out of order. It provides an efficient protecting and air regulating mechanism for the radiator, and may be adapted to various types or designs of construction, 10 or otherwise changed or varied by the skilled mechanic, without departure from the scope of the following claims.

What I claim is:

1. A radiator guard consisting of a supporting frame adapted to be spaced in front 15 of a vehicle radiator and a series of vertically arranged independently movable spring controlled pivoted vanes therein having open and closed positions and being arranged to normally remain in open position.
2. A radiator guard consisting of a supporting frame provided at top and bottom with pivoting bearings and a series of vertically arranged independently movable 20 vanes having pivoting terminals engaging

said bearings, said vanes normally being disposed at an angle to the frame and means for yieldably holding them in such position.

3. A radiator guard consisting of a supporting frame adapted to be spaced in front 30 of a radiator provided at top and bottom with pivoting bearings and a series of vertically arranged vanes having pivoting terminals engaging said bearings and a rearwardly extending arm, and a tension spring 35 connected with said arm and with a resisting abutment, said vanes normally being held by said springs in open position in which they are at an angle to the frame.

4. In combination, a rectangular hollow 40 supporting frame, means fixedly connecting it with a truck frame in front of the radiator thereof, a series of vertically arranged pivoted spring controlled vanes 45 mounted in the frame, and a cross bar extending through the sides of the frame and across the front portions of the vanes.

In testimony whereof I hereunto affix my signature.

NORMAN C. HUCKESTEIN.
